US00D814123S

(12) **United States Design Patent** (10) **Patent No.:** **US D814,123 S**
Chang et al. (45) **Date of Patent:** **** Mar. 27, 2018**

(54) **INVERSE ANIMAL FEEDER**

(71) **Applicant:** **CIXI HAOSHENG ELECTRONICS & HARDWARE CO., LTD.**, Cixi, Zhejiang (CN)

(72) **Inventors:** **Shih-Ming Chang**, Cixi (CN); **Jin-Jun Cao**, Ningbo (CN)

(73) **Assignee:** **CIXI HAOSHENG ELECTRONICS & HARDWARE CO., LTD.**, Cixi, Zhejiang (CN)

(**) **Term:** **15 Years**

(21) **Appl. No.:** **29/596,077**

(22) **Filed:** **Mar. 6, 2017**

(57) **CLAIM**

The ornamental design for an inverse animal feeder, as shown and described.

DESCRIPTION

FIG. 1 is a front perspective view of an inverse animal feeder showing my new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top plan view thereof;

FIG. 7 is a bottom plan view thereof;

FIG. 8 is the bottom perspective view thereof; and,

FIG. 9 is the top perspective view thereof.
